DESIGN FOR A SHOE

Charles Morali, Forest Hills, N. Y., assignor to
Delman, Inc., New York, N. Y.

Application March 19, 1935, Serial No. 55,944

Term of patent 3½ years

To all whom it may concern:

Be it known that I, Charles Morali, a citizen of the United States and resident of Forest Hills, in the county of Queens and State of New York, have invented a new, original, and ornamental Design for Shoes, of which the following is a specification, reference being had to the accompanying drawing, in which:

Figure 1 is a plan view, and

Figure 2 is a perspective view of a shoe, showing my new design.

The dominant features of my invention com-

prise the slender stripings latticed to define angular apertures over the vamp and over the forward portions of both quarters, the counter portion being closed and alternate apertures being filled in with a material of contrasting color to obtain the ornamental checkerboard effect.

I claim:

The ornamental design for a shoe as shown and described.

In witness whereof, I have signed my name this 12th day of March, 1935.

CHARLES MORALI.
